UNITED STATES PATENT OFFICE.

DANIEL R. SENN, OF AUGUSTA, GEORGIA, ASSIGNOR TO THE TERRELL MACHINE COMPANY, OF CHARLOTTE, NORTH CAROLINA, A CORPORATION OF NORTH CAROLINA.

BOBBIN-CLEANING MACHINE.

Application filed September 9, 1926. Serial No. 134,434.

In textile manufacturing operations, as is well known, when roving bobbins are removed (for replacement by filled bobbins) from the creels of fly-frames and spinning 5 mules, small quantities of rovings usually still remain thereon; and when filling bobbins are ejected from the working shuttles of automatic looms employing feelers, small quantities of filling, termed feeler waste, usually 10 remain thereon. Machines are in use for removing such remainders or residues from roving and filling bobbins, respectively. For example, a well-known type of bobbin 15 cleaner, which is employed for cleaning roving bobbins by removal of residues of rovings from the exteriors of the bobbin barrels, is shown and described in U. S. Letters Patent No. 1,451,239, dated April 10, 1923.

Sometimes in the case of roving bobbins 20 portions of rovings, and more or less lint or other waste, become entered within the central bores of the bobbins, and when it is sought to effect the removal thereof operations have to be performed for clearing out 25 the said bores. These operations have been performed separately from the more or less completely automatic cleaning or stripping of the bobbin exteriors, and have entailed additional handling of the bobbins, with an 30 increased amount of labor and cost.

The object of the present invention is to enable bobbins to be cleaned interiorly as well as exteriorly, in one machine, in a single passage through the machine. The invention 35 consists, accordingly, in a machine comprising, in combination, means for cleaning the exteriors of bobbins and means whereby, also, the interiors thereof are cleaned. The means for performing each division of these operations may be varied in reducing the invention 40 to practice. For cleaning the bobbin exteriors in the case of roving bobbins the means of the Letters Patent aforesaid may advantageously be employed. For cleaning out the 45 interior bores, pneumatic devices may advantageously be utilized, inasmuch as the cleaning may be effected more expeditiously thereby than by other kinds of devices. The accompanying drawings show two illustrative 50 embodiments of the invention, comprising exterior-cleaning devices on the order of those of the said Letters Patent, and blower-jet devices for clearing out the bobbin bores.

In the drawings,—

55 Fig. 1 is an end elevation of a portion of

the machine of the Letters Patent aforesaid, No. 1,451,239, of April 10, 1923, having combined therewith a bobbin supporting and guiding apron and one arrangement of blower-jet device.

Fig. 2 is a side view of the parts that are shown in Fig. 1.

Fig. 3 is a sectional detail view on an enlarged scale showing a bobbin in position for being operated upon by the jet of air from the blower-nozzle.

Figs. 4, 5 and 6 are views similar to Figs. 1, 2 and 3, showing a slightly different arrangement of parts.

Having reference to the drawings,—

At 1 is indicated a portion of the machine of the Letters Patent aforesaid for removing or stripping the residue of waste from the outside of spent bobbins, only so much of the said machine being shown as is needed for an understanding of the present invention. Preferably the device for clearing out material such as has been mentioned from the bobbin bores is applied to the discharging end of such a machine, at or near the point at which the bobbins 9, 9, after having been cleaned externally, are expelled or drop from the machine. The drawings show at the said point; that is to say, located below the aperture from which the bobbins issue, an inclined chute or apron 2, which is suitably mounted on the base 3 of the machine, and down which the externally cleaned or stripped bobbins roll.

In the case of each of the illustrative embodiments of the invention which are shown in the drawings, a current or jet of air directed lengthwise of the bobbins, in other words moving axially with respect to the bobbins, is brought to bear on them, either while they are still in the grip of the machine or as they roll down the chute or apron 2, so as to enter the bore or interior of a bobbin at one end of the latter and expel at the other end of the bobbin any fragments of roving, lint or dirt that may have lodged within the said bore or interior. Inasmuch as many bobbins have a bore that is not uniform in diameter from end to end of the bobbin but is smaller at one end than at the other, the air should be directed into the smaller end to assure free exit from the large end of the matter required to be expelled. In the case of each of the said illustrative embodiments an air-nozzle is mounted by means of an el-

- bow 6 on the upper end of an upright pipe 5 which at its lower end is connected with a source of supply of compressed air. The arrangement of the air-nozzle is such that the jet issuing from said nozzle is projected transversely across the path of movement of the externally cleaned bobbins. In Figs. 1, 2, 3, the air-nozzle 4 is located in a position which causes the jet of air to act upon the bobbins 10 as they roll down the apron or chute 2. In Figs. 4, 5 and 6, the nozzle 7 is arranged to bring the air-jet issuing therefrom in line with the bore of each bobbin the instant the latter emerges from beneath the lower edge 8 15 of the housing at the discharge opening, so as to let the air-jet enter the bore before the bobbin has gained headway in falling away from the mechanism by which the bobbin-exterior are cleaned. If desired, the nozzle may be 20 located in such position in respect to a suitable hole in the housing of the stripping machine 1, that the jet of air will register with the bores of the bobbins as they are being fed along within the machine while they still remain 25 in the grip of its feeding mechanism; in this case provision will be made for escape of the roving, lint, etc., discharged from the said bores through an opening at the opposite side of the said housing.
- 30 The use of the present invention is not confined to roving bobbins, but it is equally within the scope of the invention to apply the principles involved to the cleaning of the bores of filling bobbins.
- 35 What is claimed as the invention is:—
1. In a bobbin-stripper, the combination with mechanism for stripping residues or waste from the exterior of bobbins, and conveying means for the bobbins operated upon, 40 of a jet device located adjacent the path of the bobbins and arranged to send a jet of air through the bore of each bobbin as the latter passes the jet device.
  2. In a bobbin-stripper, the combination 45 with mechanism for stripping residues or waste from the exteriors of bobbins, and means for conveying the said bobbins with

their length disposed transversely with relation to the path of movement, of means for causing concentrated flow of air transversely 50 across said path and through the bores of the bobbins while they are moving by in succession.

3. A bobbin-stripper comprising, in combination, mechanism for stripping residues or waste from the exteriors of bobbins, and means located at the discharging end of such mechanism operating to clear out the bores of the bobbins by a concentrated jet of air moving axially with respect to the bobbins and 60 directed through the bore of each individual bobbin in succession as the respective bobbins travel past said jet in being discharged from the stripping mechanism.

4. A bobbin-cleaning machine comprising, in combination, means for stripping residues or waste from the exteriors of bobbins, a chute to carry the externally-stripped bobbins away from the said stripping means, and means for cleaning the interior of the bobbins 70 consisting in an air-nozzle connected with a source of air under pressure and directing its jet of air to enter the interiors of the bobbins as they pass along said chute.

5. A bobbin-cleaning machine comprising 75 in combination a chute down which bobbins are designed to roll, an air-nozzle located in proximity to the path followed by one end of each bobbin as it thus rolls down, and means for causing a concentrated jet of air 80 to flow from said air-nozzle through the bore of each bobbin as the latter rolls past.

6. A bobbin-cleaning machine comprising, in combination with mechanism for stripping residues or waste from the exteriors of bobbins, a chute down which bobbins are designed to roll, an air-nozzle located in proximity to the path followed by one end of each bobbin as it thus rolls down, and means for causing a concentrated jet of air to flow from 85 said air-nozzle through the bore of each bobbin as the latter rolls past.

DANIEL R. SENN.
